UNITED STATES PATENT OFFICE.

HERMAN F. W. LIEBMANN, OF CHICAGO, ILLINOIS, ASSIGNOR OF ONE-HALF
TO HENRY K. MEYER, OF SAME PLACE.

MACHINE FOR CUTTING FILES.

SPECIFICATION forming part of Letters Patent No. 271,483, dated January 30, 1883.

Application filed January 27, 1882. (No model.)

To all whom it may concern:

Be it known that I, H. F. W. LIEBMANN, of the city of Chicago, county of Cook, and State of Illinois, have invented certain Improvements in File-Cutters, of which the following is a specification.

My invention relates to an improvement in machines for cutting files, which will be hereinafter described with reference to the accompanying drawings, in which—

Figure 1 represents a side elevation of a machine embracing my improvement; Fig. 2, a cross vertical section of the same; and Fig. 3 another cross vertical section thereof, taken at right angles to the one shown in Fig. 2, and as indicated by the broken lines 3 3 in the last-named figure.

f indicates a file-blank, resting in a movable bed or box, *W*, which has two vertical sides and a horizontal flange extending out from each side and projecting over the circular flanges of the feed-roller *E'*, which is mounted upon feed-shaft *E*, having its bearings in the frame *A* of the machine. The under side of the box *W* is provided with teeth *t*, to gear with the teeth on the central portion of the feed-roller *E'*. The box *W* is held up in position by the guide-roller *F'*, which is mounted on shaft *F*, which is itself rendered adjustable vertically by its head-piece *F²* and the vertical slot in the frame, and that roller and its shaft are adjusted vertically by means of the cam *H'* on the shaft *H²* and the handle *H*, by means of which the file-blank and its box can at any time be raised up to or lowered down from the cutter *c*. The box or file-blank carrier *W* is shown in the drawings to have a bottom that is narrow in proportion to the height of its sides; but that fact is not material, since no claim is made herein for the exact proportions of said carrier. The bottom should be wide enough and the sides high enough for the reception of the file-blanks to be cut; or a number of file-blank carriers may be kept on hand for blanks of different dimensions, provided always that their side flanges shall be adapted to the feed-roller. In case the box *W* is too deep or too wide for a blank, its capacity may be made smaller by means of metal plates placed under the blank to raise it higher, or on one or both sides of the blank to render it narrower.

So, likewise, where the blank shall taper from one end toward the other, or shall be irregular in its cross-section, it may be adjusted in position, and then held by suitable plates or strips of metal or other suitable material placed inside the carrier alongside the blank, and the whole held by the set-screws *S⁴*. The feed-roller is not only toothed on its periphery, but has also teeth *E³* on its face, to be operated upon by the ratchet-lever *e*, which is pivoted to the frame at *P*, and connected with the hammer-lever *B²* by means of the connecting-bar *a*, which is adjustable along the length of ratchet-lever *e*, at its lower end, by means of set-screw *S⁵*, and at its upper end by means of the screw-shaft *S⁶*, which turns in its box *b²*, to which bar *a* is bolted.

D' is a guide-roller mounted adjustably on the shaft *D*, which is embraced by boxes *D²*, which have vertical play in the frame, and are supported by the springs *D³*, which connect the frame of the box of the shaft with the bearings of the screws *S²*, so that the height of the shaft may be regulated by the turning of the screw-shafts.

C² is a striker-arm journaled upon shaft *C⁴* upon the frame *A*, bearing in its outer end the chisel-holder *C⁶* for the chisel or cutter *c*. The chisel-holder is provided with a head, as shown, which rests upon the striker-arm *C²*, and its body is adapted to turn freely in the vertical opening for it in the arm, and may be held to any adjustment desired horizontally by means of the set-screw *S³*. The lower end of the body of the chisel-holder is provided with a vertical and rectangular socket for the cutter *c*, as shown, and the cutter itself is simply a flat rectangular bar of steel having its lower end beveled into a cutting-edge, which may be sharpened from time to time as required. It is capable of vertical adjustment only, and this is effected by simply placing suitable blocks between its upper end and the bottom of its socket in the chisel-holder, and this may be done from time to time as the cutter by wear becomes too short for use. The edge of the cutter is adjusted to any angle required to the face of the blank by turning its holder in the end of arm *C²*, where it is made fast by the set-screw *S³*. Spring *C⁵*, seated upon the frame, has the stiffness requisite for the purpose, and holds the striker-

arm C², bearing the chisel-holder and its chisel, up off the file-blank until the cam C' upon its shaft C in the frame gradually forces it down upon the blank, just before a blow is struck by the hammer-head B⁵ upon the head of the chisel-holder.

The driving-shaft B is provided with crank-arms b b, and pin b' through them, upon which swings hammer-lever B², having hammer-head B⁵, and having slot O through it, of suitable length to allow of the revolution of crank-arms and give reciprocating motion to the hammer-head B⁵. The two bearings B⁴ of the driving-shaft B are held between the points of two pairs of screw-shafts having their bearing in the frame, one pair, S, adapted to operate upon the upper side of the bearings, while the other pair, S', is adapted to operate upon their lower sides from below, and by operating these screws the bearings and the shaft may be raised and lowered and the throw of the hammer-head increased or diminished, and this can be done, to a certain extent, without throwing the gear-wheel B³, mounted on shaft B, out of gear with gear C³, mounted on the shaft C, which is designed to have the same motion imparted to it with the lever B².

The opening in cam-wheel C' is oblong in form, as shown in Fig. 3, in order that it may be adjustable and stand more or less eccentrically upon its shaft C and depress the striker-arm C² more or less, as required, the specific function of that cam being to force the cutter C down upon the file-blank and hold it so just before the blow is struck upon the head of the chisel-holder by the hammer-head B⁵. The cam C' is held to any adjustment upon its shaft C by being clamped and held fast between two screw-nuts, N and N₁, turning in different directions and working in the shaft, as shown in Fig. 2. The file-blank is held against side motion in the box or carrier W by the set-screws S⁴, as before intimated. The guide-roller D' should be made of rubber, soft wood, or other elastic material, in order that it may hold the file-blank with force enough merely to prevent its slipping endwise while it is being moved under the cutter.

The operation of the machine is as follows: By each revolution of the driving-shaft B the hammer-head B⁵ is brought down on the head of the chisel-holder C⁶ and by means of the gears B³ and C³ the cam C', with which striker-arm C² is always kept in contact by springs C⁵, forces the cutter c down on the file-blank a little before the blow is struck; but when the hammer-lever B² is first raised, in order to acquire force and momentum for the blow the end of the lever to the left of the pivot-shaft B⁶ is lowered, and by means of connecting-bar a it depresses the outer end of ratchet-lever e and raises the other end, which engages with

teeth E³ on the face of feed-wheel E' and turns the same, and thus drives file-carrier W to the left and feeds the blank to the cutter. When 65 the connecting-bar a is adjusted and fastened, by the means hereinbefore explained, further removed from the pivot-shafts B⁶ and P, more motion will be imparted to the feed-roller E', and the cuts of the chisel will be made farther 70 apart; but when that bar is brought nearer to these shafts the motion will be less and the cuts closer together. The lateral flanges extending from the bottom of the carrier W travel upon the vertical flanges of the feed-roller E', and the carrier is by that means held in a true vertical position and its movement rendered steady and even, while the feed-motion is imparted to the carrier by means of the teeth E upon the periphery of the feed-roller operating 80 upon the teeth t on the under side of the carrier. In Fig. 3 the chisel-holder is shown to have the required inclination to the face of the blank to make the cut therein at a suitable vertical angle thereto. 85

What I claim as my invention, and desire to secure by Letters Patent, is—

1. The combination of the file-blank carrier W, provided with teeth t upon its bottom, and the feed-wheel E', adapted to feed the file-blank to the cutter, substantially as described. 90

2. The combination of the feed-wheel E', provided with vertical flanges, and also with teeth between such flanges, and ratchet-teeth E³ on its outer face, and the ratchet-lever e, 95 adapted to transmit feed-motion to the carrier W from bar a, substantially as described.

3. The combination of the ratchet-lever e, hammer-lever B², screw-shaft S⁶, and connecting-bar a, with its set-screw S⁵, adapted to 100 transmit motion from hammer-lever B² to ratchet-lever e and regulate the feed-motion, substantially as described.

4. The combination of the roller F', having head-piece F² on shaft F, and the cam H' on 105 shaft H², adapted to let down, when required, the carrier W, substantially as described.

5. The guide-roller D', provided with a groove in its periphery for the side or edge of the file-blank, and side flanges for rolling-contact with 110 the like flanges of the carrier W, the said roller being elastic and adjustable, in combination with said file-carrier, substantially as and for the purpose described.

6. The cam C', mounted eccentrically and 115 adjustably upon its shaft C, and fastened in position by clamp nuts N, in combination with arm C², substantially as and for the purpose described.
